F. H. HEADLEY

METALLIC CHAIR, STOOL, SEAT, AND THE LIKE

Filed Jan. 19, 1924

UNITED STATES PATENT OFFICE.

FREDERICK H. HEADLEY, OF NORTHFIELD, NEAR BIRMINGHAM, ENGLAND.

METALLIC CHAIR, STOOL, SEAT, AND THE LIKE.

Application filed January 19, 1924, Serial No. 687,184, and in Great Britain September 18, 1923.

This invention relates to improvements in chairs and consists of the matters herein-after described and more particularly pointed out in the appended claims.

5 The primary object of the invention, is to provide a strong and rigid chair especially adapted for use in factories and similar places and which is so constructed as to ably withstand the rough usage to which it is naturally subjected.

10 A further object of the invention is to construct the chair of substantially all metal, with the parts so arranged as to afford the occupant the greatest degree of comfort and freedom of movement commensurate with 15 the surroundings in which the chair is used.

Another object of the invention is to provide an improved adjustable back rest for the chair which may quickly be arranged to 20 suit the occupant and which may be readily folded down into a position beneath the chair seat, so that the chair may be placed beneath a work bench or similar factory equipment so as to be out of the way when not occupied.

25 These objects of the invention as well as the many advantages thereof will more fully appear as I proceed with my specification.

In the drawings:—

Fig. 1 is a view in perspective of a chair embodying my invention.

30 Fig. 2 is a view in side elevation of the same.

Fig. 3 is a horizontal sectional view as taken on the line 3—3 of Fig. 2.

35 Fig. 4 is a detail vertical sectional view thru Fig. 3, as taken on the line 4—4 thereof.

Fig. 5 is a detail sectional view taken on the line 5—5 of Fig. 2.

Referring now in detail to that embodiment of the invention illustrated in the accompanying drawings;—10 indicates as a whole, the base or pedestal of the chair, and 11 indicates the seat member of the chair to which a back rest 12 is operatively connected as will later appear.

40 The base or pedestal includes two vertically spaced, metallic collars or spiders 14—14 having arcuately spaced vertically extending rounded recesses 15, in the periphery thereof. In said recesses are seated, the top ends of tubular metallic leg members 16, screws 45 passing through said leg members and extending into said collars to securely attach said leg members thereto. The bottom parts 50 of said leg members are bent outwardly

to provide a large spread for the legs so that the chair cannot easily tip over and on the extreme bottom ends are suitable antifriction members or casters 18 so that the chair as a whole, may be easily moved about upon 60 the floor.

19 indicates a tubular post or standard which has a rotative bearing as well as a vertical adjustment in centrally disposed aligned openings 20 in the collars 14. As 65 shown herein, the post or standard 19 has a plurality of vertically spaced sets of holes 21 therethrough and a pin 22 is employed which may be inserted through any one set of holes and to rest or bear at its ends upon 70 the top collar 14 to provide the desired height for the seat 11. As is apparent this adjustment may be quickly and easily made, and to prevent loss of the pin I connect it to 75 a part of the seat 12 by means of a chain or other flexible member 23, as will later appear.

To the top end of the standard is secured laterally extending arms 24 (see Fig. 2) which are attached to the seat 11 in any convenient manner, so as to support the same upon said standard. Preferably the seat has a substantially rectangular open frame which includes angle bar side members 25—25 and front and rear strap members 26 80 and 27 respectively. The ends 26^A and 27^A of said strap members are bent to overlap the upright flanges of the side angle bars 25 and are secured thereto in any suitable manner. The laterally extending arms 24 90 may be secured at their ends to the underside of the horizontal flanges of the angle bars 25 midway between their ends and on the top side of said flanges is secured the lateral margins of a flexible seat member 28 95 by means of metallic straps 29. Said seat may be of the cushioned type if so desired or it may be made of a strong textile material such as canvas. The front end frame member or bar 26 is bowed downwardly between its ends so as not to be engaged by the legs of the occupant which would render the chair uncomfortable to sit upon. To the rear end frame member 27 is attached the pin chain 23 and depending from said frame 100 member is a rod 29' which terminates in an upturned hook end 30 for a purpose to appear later.

The back rest 12 comprises horizontally spaced side arms or stays 31 in the form of 110

metallic straps. Said arms are offset inwardly midway between these ends so that the top ends 32 thereof are closer together than are the bottom ends 33 which are spaced apart a distance slightly greater than the width of the seat frame. The arms 31 are connected together just above their offset portions by a brace strap or band 34 and to the top ends 32 of both of said arms is connected an outwardly bowed bar 35 which carries a similarly shaped back rest member 36 to receive the back of the occupant. This rest member may be padded or cushioned if so desired.

15 The bottom ends 33 of said arms are operatively connected to one end of a pair of links 37 by bolts 38, the other ends of said links being pivotally connected to the front ends of the seat frame side members 25 by means of similar bolts 39, the said last mentioned bolts also extending through the bent over ends 26^a of the front frame member 26. The bottom ends 37 of the arms 31 and the associated ends of the links 37 are provided with spaced openings 40 and 41 respectively, any two of which may be brought into registry with each other to receive the bolts 38. In the upright flanges of the side member 25 of the seat frame are provided spaced holes 42 into any one of which the bolts 39 may be threaded. By reason of the provision of the holes 40—41 and 42 as before described, it is apparent that any desired angular position or adjustment of the arms 31 and back rest member 36 may be obtained.

On the inner surface of each of the arms 31 just below the offset therein, is riveted a plate 43 (see Figs. 2 and 5) which includes an offset portion adapted to engage upon the top edge of the bent over ends 27^a—27^a of the rear frame member 27. The offset portion terminates in a hook-like portion 44 and the purpose of which will shortly appear. These plates 43 support the arms 31 upon the seat frame under the pressure applied to said arms by the occupant of the chair when leaning back against the rest member 36. When it is desired to lift the chair by the back, an upward pull causes the hooked end 44^a to engage the rear cross member of the seat frame 27, thus lifting the whole chair.

When it is desired to lower the back rest member 36 until the arms 31 are in the position shown in dotted lines in Fig. 2 so that the chair may be stowed beneath a work bench or if it is desired to use the chair as a stool to support some object, as a box or the like, the back rest member is first moved forward to free the hook 44^a from the rear cross member of the seat frame and then lifted upwardly to release the offset portions 44 from engagement with the seat frame. This movement of course, is accommodated for by the links 37. Further backward and

downward movement is next imparted to the back rest member when the hooks 44 will clear the seat frame after which a forward movement is imparted to said member until the brace bar 34 engages the rod 29' before mentioned. Upon release of the back rest, the same will move downwardly under its own weight until said brace bar engages the hook 30 to retain the back in this lowered or folded position.

By reason of the arm and link construction before described, it will be noted that there are no obstructions at the sides of the seat member 11 which will interfere with the free bodily movement of the occupant of the chair.

The chair being made of substantially all metal, is strong and rigid and therefore, withstands such rough usage to which it may be subjected. It is especially adapted for a work room chair and the back rest may not only be quickly and readily adjusted as to angular position, but said back rest may be folded down so that the chair may be stowed away, as before mentioned.

While in describing my invention, I have referred to certain details of mechanical construction and arrangement of the various parts, I do not limit myself thereto except as may be pointed out in the appended claims.

I claim as my invention:

1. In a chair or the like, the combination of a seat frame, a seat member carried thereby, a back rest frame comprising two laterally spaced arms, a brace bar and a back rest member connecting the top ends of said arms together, links connecting the bottom ends of said arms with the front end of the seat frame, a hook member depending from the rear end of the frame at its middle and hook devices carried on the inner surfaces of said arms below the brace bar and adapted to hook over parts of the seat frame near its rear end to hold the back rest frame in its operative position, said hook devices being capable of being disengaged from the seat frame so that said back rest frame may be swung downwardly into a position below the seat frame, wherein the brace bar engages the depending hook member to support the back rest frame in this last mentioned position.

2. In a chair or the like, the combination of a seat frame, a seat member carried thereby, a back rest frame comprising two laterally spaced arms, links each pivotally connected at one end to the front end of the seat frame, the other end of said links and the bottom ends of said arms having a plurality of apertures therein, a pin extending through registering apertures in said arms and said link ends, a back rest member connecting the top ends of said arms and hook devices in the inner surfaces of said arms between the ends thereof adapted for en-

gagement with a part of the seat frame to hold the back rest frame in the desired angular position.

3. A back rest frame for a chair comprising two spaced arms, each of which includes an offset part between the ends thereof, so that the top ends of said arms are closer together than are the bottom ends of said arms, a member connecting the top ends of said arms together, a back rest member carried by said connecting member, a brace bar operatively connecting said arms together above said offset parts and hooks secured to the inner surface of said arms below said offset parts, the bottom end of each arm having a plurality of apertures therein.

4. A chair embodying therein, a rectangular seat frame including side and rear members, a back rest frame including side arms, a back rest connecting the top ends of said side arms, devices on said side arms adapted for a hooked engagement with the rear corners of the seat frame, and links adjustably connecting the side members of the seat frame with said side arms, which links permit various angular adjustments of the back rest frame with respect to the seat frame about said hooked engagement as a fulcrum.

5. In a chair or the like, the combination of a seat frame including side and rear members, a back rest frame including side arms and a back rest connecting the top ends thereof, links connecting the bottom ends of said arms with the side members of the seat frame, means on said arms capable of a detachable connection with said seat frame

and providing a fulcrum about which the back rest frame may be swung into the desired angular position, said links permitting the back rest frame to be shifted forwardly to free said means on said arms from the seat frame, and a member depending from and below the rear member of the seat frame to be engaged by a part of the back rest frame for supporting it in a position below the seat frame, after the back rest frame has been swung about said links to free it from the seat frame.

6. In a chair or the like, the combination of a seat frame including side and rear members, a back rest frame including side arms and a back rest connecting the top ends thereof, links connecting the bottom ends of said arms with the side members of the seat frame, means on said arms capable of a detachable connection with said seat frame and providing a fulcrum about which the back rest frame may be swung into the desired angular position, said links permitting the back rest frame to be shifted forwardly to free said means on said arms from the seat frame, a brace connecting the side arms of said back rest frame together below the back rest member, and upwardly opening hook members depending from and below the rear member of the seat frame and adapted to be engaged by said brace after said back rest frame has been swung about said links to free it from the seat frame.

In testimony whereof, I have hereunto set my hand, this 1st day of November, 1923.

FREDERICK H. HEADLEY.
